Application June 26, 1941, Serial No. 399,766

24 Claims. (Cl. 178—33)

This invention relates to apparatus for making possible the exercising of accurate control over other apparatus in response to directive signals received from outside sources which are usually located remote from the control apparatus.

The invention is especially concerned with the converting of standard telegraph code messages, as well as other types of messages, into recorded words composed of alphabetical symbols (or into other symbols of a meaningful nature, such as numerals) in proper groupings or other desired spaced relationships, relative to one another. However, the invention is broad in its conception, and embodiments thereof may be constructed for a variety of control purposes, as will be apparent to those skilled in the art.

Remote control of aircraft or of other mechanical or electrical agencies in response to complex signals may be accomplished by employing suitable embodiments of the invention. Other suitable embodiments may be constructed for receiving secret messages made up of a particular type of secret code which has certain characteristics in common with telegraph code, especially the so-called continental code, now standard for all radio-telegraphy.

A principal object of the invention is the elimination of human operators for accurately receiving informative messages, directive impressions, or the like, composed of a series of so-called dot and dash signals with interposed rests, groups of which are arranged in a distinctive and meaningful manner relative to one another.

Another object is to provide for accurately receiving the matter transmitted, whether the speed of transmission be at a slow rate or at a fast rate, or be variable in character, as in so-called heavy sending during greatly disturbed atmospheric conditions.

An object is to provide for accurately receiving the matter intended to be transmitted, within a range of faulty transmission which is considerably broader than that capable of comprehension by a human operator.

An object is to provide for either manual or automatic adjustments of the control apparatus in quickly adapting it to different speeds of signal transmission.

An object is to provide for attaining the above objects relatively simply and economically and with a minimum bulk of mechanism.

In accomplishing the foregoing objects, an outstanding feature of the invention resides in the recognition (and in the taking advantage) of the fact that while, in telegraph code, the individual

signals (dots and dashes) and the individual rest periods (spaces) do not have any prescribed lengths in terms of seconds, or other definite unit of time, they do each have a definite relative time value as respects the others. Thus, for example, the length of a dash in the continental code, which is now standard for radio-telegraphy and which may be used in telegraphy generally, is three times the length of a dot. The dot may be said to be one unit of time in length or duration and the dash three units of time, whether the particular unit of time be actually one-half, one, two, three, or more seconds in length. Also, in the continental code, the spaces or periods of rest between dots and dashes of any group of signals representing a symbol, are equal in time length, one with another. Therefore, each such space or rest period becomes a convenient reference value with which the preceding signal may be compared in determining whether that signal is a dot or a dash, this being of great importance because speed of signal transmission often varies from time to time.

It is this variation in speed of signal transmission in radio-telegraphy that has made the development of apparatus of the instant type especially difficult. And it is this difficulty which has been surmounted by the provision of means for comparing the duration of any signal with the duration of the space or rest period immediately following, and for causing a resultant action in accordance therewith.

Embodiments of the invention are, structurally speaking, equipped with means for causing physical phenomena to exist for lengths of time corresponding or related to the time lengths of the respective signals, and of the respective rests, or lack of signals, occurring in a group of such signals and rests which make up a given letter, numeral, or other symbol, and which occur between the individual groups and groupings of individual groups. Other means are provided for actuation, in response to the effects of certain combinations of certain of the physical phenomena, in accomplishing the end result, which may be the selecting and pressing of proper keys of an ordinary typewriter, if letters or numerals are to be printed, or the pressing of the space bar thereof, if there is to be spacing of printed symbols or words. The end result, however, may be the selective actuation of certain controls of a motivated mechanism, such as an airplane, or of certain valves, dampers, etc. in other types of apparatus, all in proper order and timing relative to one another.

For translating the series of meaningfully arranged signals and rests, as received, into such a desired purposeful result as the typing out of alphabetical, numerical, or other symbols to accord with a message transmitted in code, there are preferably provided, pursuant to the invention, several serially correlated devices for converting the respective signals, and the normal periods of rest therebetween, into therewith correspondingly or relatively determined effects, which effects are further utilized in determining the nature of the end result, or the series of end results, accomplished by the apparatus of the invention.

Further objects and features of the invention, and further generic characteristics thereof, will be apparent from the following detailed description of preferred specific embodiments.

In the drawings, which illustrate the invention embodied in mechanism particularly adapted for translating radio-telegraph messages, as received in continental code, into their equivalents expressed in words, numerals, and other usual symbols, typewritten:

Fig. 1 represents a side elevation of a manually regulated mechanism completely assembled and ready for use, minor portions of supporting framework being broken out to reveal otherwise hidden parts;

the apparatus of Fig. 1, the views of each translating mechanism being similar to those illustrated in Figs. 15, 16, and 17, but reduced somewhat in size, and the series of views illustrating the relative positions of the several mechanisms after the several telegraphic signals of the message of Fig. 18 have been mechanically recorded by the apparatus in successive letter groups;

Fig. 20, a view similar to that of Fig. 2, but illustrating another embodiment of the invention designed for automatic regulation in accordance with variations in speed of message transmission, portions of the mechanism being broken away for convenience of illustration;

Fig. 21, a view somewhat similar to the upper left-hand portion of Fig. 1, wherein the speed regulator for the several translating mechanisms and for the timing mechanism, is illustrated, the present view, however, being of the automatically controlled embodiment illustrated in Fig. 20;

Fig. 22, a view taken on the line 22—22, Fig. 21, considerably enlarged;

Fig. 23, an enlarged, fragmentary side elevation, taken from the left toward the right, in Fig. 22, and showing, in addition, an electrical actuating device;

Fig. 24, a detail view in vertical section, considerably enlarged and taken centrally through one of the box-like portions of the apparatus appearing in Fig. 20;

Fig. 25, a fragmentary, condensed, top plan view of that portion of Fig. 21 which appears to the extreme left; and

Fig. 26, a wiring diagram illustrating the electrical elements and wiring connections additionally employed in the wiring diagram of Fig. 11, for the automatically regulated apparatus of Figs. 20 through 25.

The illustrated apparatus merely exemplifies the practical implications inherent in the generic concepts of the invention. Those skilled in the art will readily appreciate that other well-known devices may be adopted and properly correlated in carrying out the purposes of the specifically illustrated and described embodiment, and will realize that somewhat similar embodiments can be constructed for accomplishing a variety of other end results, such as those set forth hereinbefore.

Since the continental code is more widely used than any other and has characteristics well adapting it for mechanical or automatic reception, that which here follows has particular reference to its use, although simple changes will make other codes also possible of use.

The illustrated apparatus translates continental code messages, as and when received, into ordinary typewritten messages capable of being read by the average man.

Considering, for a moment, the characteristic nature of the continental code, the dot and dash signals thereof are separated, one from the other, by spaces or rests of standard lengths or durations. A group of dots and/or dashes (and, in two instances, for the letters "e" and "t," a dot and a dash alone, respectively) is used to indicate a letter, numeral, or other symbol. The individual signals in any symbol group are spaced by rests which are equal in duration to the length of a dot, and the individual symbol groups, corresponding to letters, numerals, etc., are spaced by rests equal in duration to three of the first type of rests. The individual groupings of symbol groups, corresponding to words, num-

bers, etc., are spaced by rests equal in duration to five of the first type of rests.

In radio-telegraphy, when weather conditions are such as to produce much static, or interference with the signals transmitted, it is necessary that the dots, dashes, and rests be considerably longer than otherwise (this is so-called "heavy sending"), so that, if portions of the signals are blotted out, there will be enough remaining to at least convey the sense of the message. This, then, means that speed of signal transmission will vary from time to time, as it will, also, but to a lesser extent, by reason of the individual capacities and characteristics of human telegraph operators sending messages.

Preliminary descriptive outline

In order to accommodate changes of speed made during the sending of messages, the receiving apparatus is provided with means for establishing a comparative relationship, expressed in physical form, between a signal and the rest (space) which immediately follows. This comparative relationship indicates whether the received signal is a dot or a dash, for it must be remembered that the standard rest between individual signals is a constant, relative to the dot and dash signals, it being, in the continental code, equal in time length to the time length of a dot, and, similarly, one-third the time length of a dash.

The means for establishing such comparative relationships as are mentioned above, may take a variety of physical forms in the various embodiments which are possible of construction pursuant to the generic concepts of the invention. In the illustrated instance, pairs of axially aligned and individually and rotatably mounted cams, indicated 10 and 11, respectively, Fig. 2, serve this purpose. One, that indicated 10, is designated a "character" cam because it is actuated in response to a received signal, and the other, indicated 11, is designated a "space" cam, because it is actuated in response to the period of rest which immediately follows the said received signal. The character cam 10 rotates through a number of angular degrees determined by the time length of the received signal, and the space cam 11 rotates through a number of angular degrees determined, for the most part, by the time length of the rest which immediately follows said signal.

For the purpose of establishing easily ascertained comparative relationships between the two cams, and for other reasons hereinafter made clear, the space cam 11 is arbitrarily made to rotate at twice the speed of the character cam 10. The relative positions of the two cams at the ends of their respective periods of rotation determine, as will hereinafter be made clear, whether the impression made on the remainder of the apparatus is one corresponding to a dot or one corresponding to a dash.

It should be understood that two cams mounted for independent rotation relative to each other, represent only one convenient way of establishing the comparative relationship between an incoming signal and a rest which immediately follows the signal. Other means differing widely in physical characteristics, may be employed. For instance, two lights, which are capable of variation in their respective intensities, and are adapted to impress their resulting comparative relationship on photoelectric cells, may be employed, or even a single source of light with a

single photoelectric cell which causes one electrical circuit to close and to remain closed while the light is on, and which causes a second electrical circuit to close and to remain closed while the light is off. Variation in respective sound intensities, in respective gas or fluid pressures, in respective linear or angular motions, or variations in other respective measurable physical phenomena may be utilized in practical embodiments of the invention for the purpose described. The important thing is that other portions of the apparatus be set into such operation as is appropriate to a dot or a dash, as the case may be.

Since most letters and other symbols are represented in code by a group of equally spaced dot and dash signals, the machine is equipped with a plurality of mutually identical character-and-space-cam translating units (or with other units comprising corresponding translating means, as aforementioned) mutually correlated, and determined in number by the maximum number of signals making up any group which it is desired the machine shall receive. In the present instance the machine is equipped with four character and space cam translating units designated 1CS, 2CS, 3CS, and 4CS in Figs. 1 and 11.

These CS translating units are placed in sequential series correlation, and operate in sequence, from the first on down the line; the first translating the first signal of the group into the desired impression on another part of the machine, which in this instance is a form structure or permutation device whose pattern depends on the type of impressions it receives, the second translating the second signal, etc.

For the purpose of this preliminary outline, it may be said that the scheme of the present embodiment is completed by the provision of means for determining when a set of notched plates, each bearing a typewriter-key-depressing pin, shall be given, as a group, an impetus which carries them toward and against the form structure or permutation device, as patterned by the received and translated signals of the group, so that that one plate which is notched in accordance with the particular pattern of the form structure or permutation device, may travel farther than the remainder, and its pin strike and depress the particular typewriter key with which that one plate is correlated, and, further for determining when the space bar of the typewriter shall be depressed to space word groupings of letters, or other similar groupings of other individual symbols, from similar groupings, such determining means including the unit designated WL, Fig. 1; the scheme being further completed by the provision of a speed regulator, designated R in Fig. 1, which keeps the entire machine in synchronism with the changing speeds of code transmission.

The translating mechanism

The character cam 10 of each CS translating unit is mounted for rotation on a stub shaft 12, which extends from one face of a supporting standard 13, and which, in turn, is solidly supported by a base framework 14, see especially Fig. 2. The space cam 11 of each CS unit is mounted for rotation on a stub shaft, 15, which extends from the opposite face of the supporting standard 13 in axial alignment with the stub shaft 12. A solenoid 16 is supported on a frame member 17 adjacent the character cam 10, and is connected for electrical energization when a

signal is transmitted and received, as by the telegraph sending key and wiring, designated generally 18, and usually located remote from the control apparatus. Likewise, a solenoid 19 is supported on a frame member 20 adjacent the space cam 11, and is connected for electrical actuation when the telegraph key of 18 is at rest position between signals. The complete electrical layout is illustrated diagrammatically in Fig. 13, and will be explained in due course hereinafter. It should be kept in mind now, however, that the electrical circuit 18 is intended to comprehend sending and receiving apparatus common either in radio telegraphy or telephony generally.

The solenoid 16 is adapted to be temporarily connected to the character cam 10, and the solenoid 19 is adapted to be temporarily connected to the space cam 11—all as determined by the received signals and the rest periods therebetween—by mechanism which is mutually identical in every respect. Accordingly, corresponding numbers will be given corresponding parts.

These mechanisms for temporarily connecting the solenoids 16 and 19 to the character cam 10 and the space cam 11, respectively, comprise respective drive elements associated with respective clutch means.

There are provided, between the solenoid 16 and the character cam 10, and between the solenoid 19 and the space cam 11, rocker arm elements 20, 20, respectively, rotatably mounted on the respective fixed shafts 21, 21, which extend longitudinally along the CS units and the WL mechanism, see Fig. 1. The lower arms 20a, 20a thereof have projecting pins 20b, 20b which slidably engage the slots 22, 22 of the solenoid plungers 16a and 19a, respectively. The upper arms 20b, 20b of the rocker elements 20, 20 are formed as shoes which function to push the respective drive elements toward the character cam 10 and space cam 11, respectively. The shoes are each provided with a recess 24 for accommodating the respective stub shafts 12 and 15 during the pushing, i. e., pressing, operation.

The drive elements 23, 23, are mounted for free rotation on the ends of stub shafts 12 and 15, respectively, and are formed with sprocket disk portions 23a, 23a, respectively, and with clutch disk portions 23b, 23b, respectively. They are normally urged outwardly toward the shoes 20b, 20b, by means of coil springs 25, 25 mounted on the respective stub shafts 12 and 15.

Light drive chains 26 and 27 run over the sprockets 23a, 23a, respectively, of each CS unit, and serve to continually rotate the respective drive elements 23, 23, of all CS units, during operation of the machine, see especially Fig. 1. In doing this, they pass over sets of respective idler sprockets 29, 29, respectively, mounted for free rotation in the bifurcated yokes 30, 30, such yokes having threaded shanks 30a, 30a, which are threaded into bracket supports 31, 31, they, in turn, being bolted to the base framework 14. The yokes 30, 30 are adjustably positioned by means of the respective lock nuts 32, 32, threaded on the shanks 30a, 30a.

There is a set of idler sprockets 29, 29 between each two adjacent CS units, as is illustrated in Fig. 1. There are also corresponding sets of idler sprockets placed on opposite sides of the WL unit, see Fig. 1, as well as a set of return idler sprockets, indicated 33, placed forwardly of the first CS unit, and a similar set, designated 34, disposed rearwardly of the WL unit.

Since no single letter in the continental code exceeds four signals equally spaced in a group, there need be only four CS translating units provided in the apparatus when only letters are to be received. If numerals, which are each composed of five signals equally spaced in a single group, are to be received, the apparatus must then be provided with a fifth CS translating unit which would be added to the series illustrated in Fig. 1, as 5CS. In like manner, if symbols are to be received which are represented by a single group of more than five signals equally spaced, then the apparatus will be provided with a number of CS translating units which corresponds to the number of signals in such single group.

The CS translating units are mounted, along with the WL unit, in a framework made up of upper frame elements 28, 28 supported by end standards 35 and 36, the entire apparatus being mounted on the base frame 14.

In back of the framework containing the CS translating units are mounted a constant speed motor 38 and a speed reducing device 39. Spaced apart on the output shaft 40 of the speed reducing device 39, see particularly Figs. 9 and 10, are mounted sprocket wheels 41 and 42, see Figs. 13 and 14, the first being in alignment with that series of sprockets 23a which are associated with the space cams of the CS units, and the second 30 being in alignment with that series of sprockets 23a which are associated with the character cams of the CS units. The sprocket wheel 42 has only one-half the diameter of sprocket wheel 41.

The drive chain 26 passes over and engages the smaller sprocket wheel 42, as well as all of those sprockets 23a which are associated with the character cams 10. The drive chain 27 passes over and engages the larger sprocket wheel 41, as well as all of those sprockets 23a which are associated with the space cams 11. Thus, the space cams 11, when properly engaged by their associated clutch mechanisms, will rotate at twice the speed at which the character cams 10 rotate when engaged by their associated clutch mechanisms.

The clutch-shoe carrying arms 20b, 20b of the respective clutch mechanisms are adapted to abut, when the clutch mechanisms are disengaged, against limit stops provided by machine screws 45, 45, which are threaded through longitudinal frame elements 46, 46. These frame elements are, in turn, secured to the frame end standards 35 and 36.

Each clutch disk 23b is perforated at closely spaced intervals adjacent the rim thereof, see 55 Fig. 2. Each cam 10 is provided with a projecting post 48, having an engaging pin 48a projecting from the end thereof for engagement with any one of the perforations 47 when the associated drive element 23 is pressed thereagainst. Likewise, each space cam 11 is provided with a projecting post 49, which, in turn, has an engaging pin 49a projecting from the end thereof for engagement with any one of the perforations 65 47 when its associated drive element 23 is pressed thereagainst.

When electrical current surges through either solenoid 16 or solenoid 19, and forces the plunger 16a or the plunger 19a outwardly, either one 70 or the other of drive elements 20, 20 are actuated to push either one or the other of drive elements 23, 23 into engagement with either the projecting pin 48a of the character cam or the projecting pin 49a of the space cam. The continually rotating drive elements 23, 23, therefore,

transmit rotative motion to the character cam and the space cam, respectively, for such periods of time as their respective solenoids are actuated.

For preventing the rotative momentum from carrying the character and space cams farther along their rotative paths than is done under the directive influence of solenoids 16 and 19, respectively, there are provided friction brakes, which are operative at all times except when the character cams and space cams are being returned to their initial positions. Mounted on longitudinal rocker shafts 51, 51 are rocker arm elements 52, 52 having upper arms 52a, 52a provided with friction pads 53, 53, which normally ride against the outer faces of the character cams 10 and the space cams 11, respectively, under pressure caused by pressure exerted on the respective lower arms 52b, 52b by respective coil springs 54, 54, which operate against the supporting standards 13. For releasing the pressure of the friction brakes on the character cams and space cams, there are provided rocker arms 55, 55 mounted on respective longitudinal rocker shafts 56, 56. These rocker shafts are adapted to carry the respective rocker arms 55, 55, and to press them against the lower rocker arms 52b, 52b of the rocker arm elements 52, 52, thus overcoming the tension stresses of the coil springs 54, 54, and relieving pressure of friction pads 53, 53 against the character and space cams. The rocker shafts 56, 56 are actuated only at such times as it is desired to return the character cams and space cams to their initial positions. Operation thereof will be explained in detail hereinafter.

For motivating the character cams and space cams to initial positions at such times as pressure of the friction brakes are relieved, flexible cords 57, 57 are wrapped about hubs 10a and 11a, respectively, of the respective character cams 10 and space cams 11, and are attached, at their lower ends, to respective coil springs 58, 58, which are anchored to the supporting standards 13. When the character cams and space cams rotate, they stretch the coil springs 58, 58, and, when the friction brakes are released, are returned to initial position by the resilient action of such springs.

For physically recording the comparative relationship established between a character cam 10 and its associated space cam 11 when a signal and the space that there follows are received, a switch box 60, carrying the two switch pins 61 and 62, is mounted on each space cam so that the switch pins extend toward and into contact with the inner face of the character cam. The switch pins rigidly carry movable contact elements 61a and 62a, respectively, which normally make electrical contact with stationary contact elements 63 and 64, respectively, under pressure of the respective coil springs 65 and 66.

The inner face of each character cam 10 is recessed, as is illustrated in Fig. 14, there being an upper recess 61 and a lower recess 68 which overlap. The switch pins 61 and 62 are positioned to extend into the respective rotative paths of these two recesses. It should be noted that both the switch pin 61 and the switch pin 62 ride, under the pressure of the respective springs 65 and 66, against the inner face of the character cam as it rotates. Accordingly, they drop into their respective recesses 67 and 68 at

appropriate times during rotation of the character cam.

As is clearly illustrated in Figs. 15, 16, and 17, there are three different positions the switch pins 61 and 62 may occupy relative to each other within the limits of the rotative path of the character cam. The switch pins 61 and 62 may both extend into their respective recesses 67 and 68, as in Fig. 15, thus closing their respective switches. This position is assumed after every re-setting of the machine in preparation for the next series of signals, and also when both the character cam and the space cam rotate through an equal number of angular degrees. As in Fig. 16, the switch pin 61 may extend into the recess 67, thus closing its switch, while the switch pin 62 remains pressed against the face of the character cam and leaves its switch open. This relationship corresponds to a dot signal, and is achieved when the character cam has rotated for one unit of time, that is, through X degrees, and when the space cam has, thereafter, also rotated for one unit of time, that is, through $2X$ degrees considering that the space cam rotates at twice the speed of the character cam. Again, as in Fig. 17, the switch pin 61 may remain pressed against the face of the character cam leaving its switch open, while the switch pin 62 extends into the recess 68 and closes its switch. This relationship corresponds to a dash signal, and is achieved when the character cam has rotated for three units of time, that is, through $3X$ degrees, and when the space cam has, thereafter, rotated for its one unit of time, that is, through $2X$ degrees, corresponding to the standard rest or space between individual signals of a group.

The switches of switch pins 61 and 62 control electrical circuits arranged to set the various component parts of the form structure or permutation device in a pattern representing the received signal, either the dot or the dash, whichever the case may be. The form structure or permutation device is adapted to be patterned in accordance with the received signals as translated by the respective CS units. It will be described in detail hereinafter, as will, likewise, the cooperating mechanism for printing the letters or other symbols.

As is apparent from Figs. 15, 16, and 17, the recesses 67 and 68 are so dimensioned and placed relative to each other that, when the character cam 10 and the space cam 11 rotate an equal number of degrees, they stand in a no-signal position; further, that when the character cam falls short of X degrees by any number of angular degrees down to zero, or over-rides X degrees up to just short of $2X$ degrees, the two cams will still register the same dot signal they would if the signal had been sent accurately, i. e., exactly X degrees; and, likewise, that when the character cam falls short of $3X$ degrees by any number of angular degrees which still carry it beyond $2X$ degrees, or when it over-rides $3X$ degrees, the two cams will still register the same dash signal they would if the signal had been sent accurately, i. e., exactly $3X$ degrees. In this way, the apparatus allows for faulty transmission to an extent which would not be possible were the signals to be received by a human operator.

When the machine is initially set for receiving a message, the character cams 10 and the space cams 11 are all at the indicated no-signal position, their respective cam fingers 10b and 11b

resting on the respective stop pieces 69, 69, and the switch pins 61, 62 being in mutually similar positions—in the present embodiment, both being pressed into their respective recesses so that the movable contact elements 61a and 62a contact the stationary contact elements 63 and 64, respectively. In another embodiment, both switch pins might rest on the face of the cam, rather than in the recesses, at this no signal position.

Each character cam is arbitrarily limited in its possible extent of rotative travel, such extent being determined by the placement of a limit switch 10—1 fixed to the supporting framework of the machine, see Fig. 8.

The extent of rotation of each space cam is limited only by the possible settings of the speed regulator R.

The speed regulating mechanism

The speed regulator R is constructed and arranged for correlating the respective CS translating units with one another and with the WL unit. It extends into operative association with each of the space cams of the CS units. It comprises several bridge elements 10, corresponding in number to the number of CS units, there being one also for the WL unit. These bridge elements 10 are mounted for swinging movement over their respective units, and, for this purpose, are pivoted at their lower ends to the longitudinal frame side elements 28, 28, being secured by means of adjustable nuts, as indicated at 71, Fig. 2, in direct axial alignment with the character and space cams of the respective units. Longitudinal connecting links 72, 72 are pivotally secured to, and along, the several bridge elements at respective sides thereof. Thus, all the bridge elements 10 move in unison, and correspondingly, when any one of them is moved.

Secured to the cross members of those respective bridge elements 10 which are associated with the CS units, are switch boxes 73, each provided with two switches 74 and 75, having side-by-side actuating fingers 74a and 75a, respectively, extending downwardly therefrom into the path of travel of lug 11b of the associated space cam, the actuating finger 74a being positioned slightly in advance of its companion. Switch 74 is normally open and controls a circuit which is arranged to set a cam element of the WL unit in operation, as explained hereinafter, and is, therefore, termed the "letter cam switch." Switch 75 is normally closed, and controls the circuit which supplies current to its associated space cam solenoid 19, and is, thus, adapted to stop rotation of its associated space cam. It is termed the "space cam limit switch."

During operation of the machine, and on loosening the nuts 71, 71, the regulator R may be manually swung forwardly or backwardly to compensate for variations in speed of transmission of the code signals. It will be remembered that, in the continental code, the rests or spaces between individual signals of a group are each only one unit of time, and that a particular space cam, rotating twice as fast as its associated character cam, travels through 2X degrees in that one unit of time. Since the movements of the space cams are functions of substantially a constant, so far as the transmitted and received code is concerned, they furnish reference devices with which the rest of the apparatus is continually kept synchronized by means of the regulator R. When the speed of signal transmission

increases, the regulator R should be swung backwardly, that is, to the left, in Fig. 1, and when the speed of signal transmission decreases, the regulator R should be swung forwardly, that is, to the right in Fig. 1.

The space timing mechanism

Since the letters or other symbols which are each represented in code by a group of several signals, equally spaced, must themselves be spaced in forming a word, number, or the like, and since the groups of letters or other symbols making up words, or the like, must themselves be spaced to form an intelligible written message, mechanism for carrying out such spacing is provided. This mechanism has hereinbefore been designated the WL unit.

Referring, now, particularly to Fig. 3, the WL unit comprises two cams mounted in axial alignment for rotation independently of each other. These cams are preferably, and are here illustrated as being, identical with the various character and space cams of the hereinbefore described CS translating units. The two cams of the WL unit are mounted in series alignment with the character and space cams of the respective CS translating units of the series of such units. One of the cams, designated 80 and termed the word cam, is aligned with the series of character cams 10, and the other, designated 81 and termed the letter cam, is aligned with the series of space cams 11. Both the word cam 80 and the letter cam 81 are arranged to be rotated at desired times by the same chain drives 26 and 27, respectively, which serve to rotate the several character cams 10 and space cams 11. Respective drive elements 82, 82, corresponding to the drive elements 23, 23, of Fig. 2, are provided, as well as solenoids and clutch mechanisms, which, likewise, correspond to those of Fig. 2. The respective solenoids 83 and 84, corresponding to the solenoids 16 and 19 of Fig. 2, serve, through the medium of respective rocker arm elements 85, 85—which correspond to the rocker elements 20, 20 of Fig. 2—to push the respective drive elements 82, 82 into engagement with the engaging pins 86a and 87a of projecting posts 86 and 87, respectively, the latter corresponding to the respective engaging fingers 48a and 49a of the projecting posts 48 and 49 in Fig. 2. As in Fig. 2, limit stops are provided for the respective rocker arm elements 85, 85, by means of machine screws, here designated 88, 88, threaded through the longitudinal frame elements 46, 46, and the drive elements 82, 82 are returned to their non-engaged position by respective coil springs 89, 89, disposed between the drive elements 82, 82 and their associated cams.

60 The word cam 80 and the letter cam 81 function merely to mark time, so to speak, and to trip certain switches. Accordingly, they are returned to their initial positions immediately upon disengagement of their respective clutch mechanisms. No friction brake mechanisms are necessary, and none are provided. Mechanism for returning the word cam and the letter cam to their initial positions are, however, provided. These are identical with those associated with the respective character and space cams. Cords 90, 90 have their upper portions wrapped around hubs 80a and 81a, respectively, and have their lower ends secured to respective coil springs 91, 91, which are, in turn, anchored to the base framework.

Secured to the cross bar of that bridge element 70, of speed regulator R, which is associated with the WL unit, are switch boards 92 and 93. The switch board 92 comprises a single switch 94 having an actuating finger 94a extending down into the path of travel of projecting lug 80b of the word cam, and the switch board 93 comprises three separate switches 95, 96, and 97 having side-by-side actuating fingers 95a, 96a, and 97a, respectively, extending downwardly therefrom into the path of travel of projecting lug 81b of letter cam 81.

The actuating fingers 95a, 96a, and 97a, while disposed in side-by-side relationship, are, nevertheless, staggered in positions, the finger 95a being more advanced than the finger 96a, and the finger 96a being more advanced than the finger 97a, so that the lug 81b of the letter cam first actuates switch 95, then switch 96, and finally switch 97.

The switch 95 is normally open, and controls the electrical circuit which sets the word cam 80 into operation; the switch 96 is also normally open, and controls the electrical circuit which is arranged to cause appropriately notched plates to drop onto the patterned form structure, whereby an appropriate letter, numeral, or other symbol is printed; but the switch 97 is normally closed, and controls an electrical circuit which is arranged to return the letter cam 81 to its initial position. Switch 95 may, therefore, be designated the "word cam switch," switch 96, the "printing switch," and switch 97, the "letter cam limit switch."

The switch 94, normally open, controls an electrical circuit which is arranged to actuate the space bar of the typewriter and to also return the word cam 80 to its initial position. It may be termed the "word spacing switch."

Since the rests or spaces between individual letters, or other symbols made up of groups of signals, are three units of time, or 3X degrees in length, and since the rests or spaces between individual groupings of words, or similar groups of single symbols, are five units of time, or 5X degrees, in length, ample time is allowed for the resetting of the CS translating units, and for the printing of the letters, or other symbols, while the word cam 80 marks time, so to speak. It can be seen, therefore, that the WL unit functions as a timer, as well as an initiator of certain ultimate actions by the apparatus after each operation of a CS unit, if allowed to so act by the inactivity of a succeeding CS unit of the series. This will be explained further herein-after.

The selective printing mechanism

The form structure or permutation device mentioned hereinbefore comprises a series of up-standing, movable form or permutation device plates, designated 1X, 1Y, 2X, 2Y, 3X, 3Y, 4X, and 4Y, respectively, Figs. 1, 9, and 10, spaced apart face-to-face, and respectively pivoted, mutually similarly and adjacent their lower ends, for limited rocking or swinging movement along respective lengthwise axes, see especially Fig. 9. They are mounted between two mutually spaced standards 98, 99, which are secured upon supporting table 37. Each form plate has pintles 99, 99 journaled in corresponding openings in the standards 98, 99, and has, also, a depending ear 99-1, which acts as a short lever arm, while the form plate proper acts as a long lever arm. There is a coil spring 100 for each form plate, each being an-

chored, at one end, to the short lever arm 99-1, and, at the other end, to the base framework at an offset location thereof, see Fig. 1, in such manner that the spring is tensioned at an angle, the angles for all the springs being substantially equal and similar. The form plates are, therefore, all held, normally, at definite and mutually identical angles to the vertical.

- Solenoids are provided for actuating the respective form plates against the tensions of respective springs 100, the solenoids being arranged in pairs, each pair of which is correlated with a certain CS translating unit. Each solenoid is connected to a corresponding one of the form plates. 10 The solenoids are designated, see Figs. 10 and 11, 1XS, 1YS, 2XS, 2YS, 3XS, 3YS, 4XS, and 4YS, respectively, to correspond with the designations of the respective form plates, and are connected to their respective form plates by means of cords, 15 designated 1XC, 1YC, 2XC, 2YC, 3XC, 3YC, 4XC, and 4YC, which pass over respective sheaves, indicated at 101, Fig. 1, the sheaves being themselves mounted for independent rotation in a housing 102, through which the cords extend. 20 The solenoids are secured in respective brackets 103, and the brackets are mounted in pairs, back-to-back, on a supporting hanger 104, see especially Fig. 9. The supporting hanger is secured to the under face of an overhanging portion of the top wall 105 of a slide box, which is formed by the stated top cover and by side walls 106 and 107. The housing 102 is secured to the outside face of, and is supported by, the side wall 106. 25 The form or permutation plates 1X, 1Y, 2X, 2Y, etc., considered collectively, are adapted to be variously patterned by the swinging of one or more thereof in one or the other of its, or of their, two limit positions, that is, either in normal rest position, as held by the action of the spring or springs 100, or in swung position, as determined by the pull of its solenoid, or of their respective solenoids, acting through its connection cord or through their connection cords. 30 The solenoid 1XS is connected in the electric circuit controlled by switch pin 61 of the 1CS translating unit, and is actuated when the 1CS translating unit translates a dot signal in the manner explained hereinbefore. Accordingly, the 1X form plate is swung to its swung limit position when the 1CS translating unit translates a dot signal. The 1YS solenoid is connected in the electric circuit controlled by switch pin 62 of the 1CS translating unit, and, accordingly, is actuated when the 1CS translating unit translates a dash signal. Actuation of solenoid 1YS swings the 1Y form plate to its swung limit position. Likewise, for the other CS translating units. If the received and translated signal is a dot, the corresponding X form plate will be swung, but, if the received and translated signal is a dash, the corresponding Y form plate will be swung. 45 In this manner, a signal, either a dot or a dash, received by a particular one of the sequential CS translating units operating in turn, is recorded in terms of a distinctive setting of a particular portion of the form structure or permutation device. Since the character cams and space cams of the several CS translating units are retained in their displaced conditions following the reception of signals, and until a letter or other symbol is printed, the distinctively set particular portions of the form structure or permutation device 50 collectively make up a pattern which accurately 55 60 65 70 75

represents a group of equally spaced signals constituting a single letter, or other symbol.

For cooperation with the form structure or permutation device in printing letters, or other symbols, there are provided a plurality of variously notched template plates which are each equipped with means for depressing a key of a typewriter T, or other similar recording device, associated with the apparatus. These template plates are disposed above the form plates, each extending transversely thereacross, and are correlated with particular keys of the typewriter T.

The respective template plates are indicated 108, and the notches therein 109, see Fig. 1, and the inner faces of side walls 106 and 107 of the slide box are grooved to form slideways for receiving them in relatively closely spaced face-to-face formation. The template plates 108 are yieldably suspended in their respective slideways by means of respective springs 110, which are secured to the tops thereof and pass through an aperture 111, in the cover element 105, to loop around respective sets of sheaves 112, 112. The sheaves are rotatably mounted in the housing 113, supported on top of the cover element 105.

The template plates 108 are given downward momentum, as a group or unit, when a letter or other symbol is to be printed, by an impact bar 114, which extends across the top edges thereof and is substantially contiguous with such top edges without exerting pressure thereon. An upstanding stem 115 is secured substantially centrally of the impact bar 114, and passes upwardly through the aperture 111, through the housing 113, and through an aperture formed in the top of housing 113, to pivotal connection with the link 116. A solenoid 117, of sufficient capacity to accomplish its appointed function, is mounted on the top cover element 105. A lever arm 118 is pivotally secured, at one of its ends, to the plunger 119 of the solenoid. Its other end is pivotally secured to the rigid standard 120, which is part of the framework of the apparatus. The link 116 is pivoted to the lever arm 118 at an intermediate location thereof, so that, when solenoid 117 is energized and rapidly pulls its plunger 119, the impact bar 114 is forced rapidly downward, with the result that the respective template plates 108 are struck thereby, and are caused to move downwardly against the tension of their suspension springs 110 with considerable momentum. The template plates, all except a particular one whose notches 109 conform to the particular pattern of the form structure, are brought to a stop by the upstanding ends of form plates 1X, 1Y, 2X, 2Y, etc., of the form structure as patterned by the received signals. That one template plate, not stopped by the patterned form structure or permutation device, continues to descend until its key-depressing pin actuates its correlated key of the typewriter T, see especially Figs. 1 and 8. It should be noted that the notches 109 in each template plate are arranged arbitrarily, in accordance with that particular distinctive pattern of the form structure which corresponds to the code representation of the particular letter, or other symbol, which the particular template plate is called upon to cause to be typed out.

The typewriter T may be any standard make, but is preferably one equipped with a continuous paper-strip feeding attachment (not illustrated), such attachments being well known, and not forming any part, per se, of the present invention. With such an attachment, a strip of paper, or other suitable material, is arranged to move

across the platen of the typewriter continuously, so that there need be no spacing of horizontal lines of print, vertically, along a sheet of paper.

The typewriter T is supported on a pedestal 121, which may rest upon the table support 31, the typewriter keyboard extending toward the plurality of template plates 108. The side wall 107 of the slide box is apertured, as at 122, to accommodate projecting arms 108a of the respective template plates, such arms being of various lengths depending upon the placement of the particular typewriter keys with which they are correlated. Key-striking pins 123, of proper respective lengths, are rigidly secured to the ends of respective arms 108a. Thus, it can be seen that, upon energization of the solenoid 117, a particular template plate 108 will be caused to move downwardly farther than any of the others, depending upon the particular pattern of the form mechanism, and its pin 123 will strike and depress a particular key 124 of the typewriter, resulting in the printing of a letter, or other symbol, corresponding to a received signal, or to a single group of equally spaced received signals.

A relatively small solenoid, 125, is provided for pulling down the space bar 126 of the typewriter T at appropriate intervals, as will be explained hereinafter, and the space bar 126 is provided with a depending pin 127. For shutting off the supply of current to solenoid 125, a limit switch, indicated generally 128, extends outwardly from its support on pedestal 121 into the path of travel of depending pin 127, thus being adapted for actuation by pin 127 at the bottom of the stroke of space bar 126.

Other known types of printing mechanisms, selectively controlled by electrical circuits which are themselves controlled by the switch pins 61 and 62, may be used in other embodiments of the invention to replace the form structure and typewriter of the illustrated embodiment.

The electrical system

Referring now to Figs. 1 and 11, and especially the latter, which diagrammatically illustrates the electric wiring of the apparatus, as well as certain of the component mechanism: A relay 135 comprising a solenoid 135a and a switch throw arm 135b may be connected to the output, indicated 134, of a radio receiving device, or to telegraph wires, for keying the input, or main keyed, circuit of the apparatus. It should be realized, however, that such input circuit may be keyed in some other manner, or from some other source, so long as it is keyed in accordance with the requirements of the particular embodiment of the invention—here, in accordance with continental code signals or the like. A double keying relay 136, a single step switch 137, and a double step switch 138 are all connected in the input, i. e., main keyed, circuit of the apparatus in such manner that the solenoids thereof operate in parallel, and so that all of them, as a group, may be keyed by relay 135, or by other suitable means.

The double keying relay 136 comprises a throw arm 136a, which has a double contact end 136b adapted to make and break with the upper and lower stationary contact points 136c and 136d, respectively, normally making with the upper stationary contact point 136c under the action of coil spring 136e, but, when the solenoid 136f of the relay is energized, making with the lower stationary contact point 136d.

The single step switch 137 comprises a throw arm 137a having a pawl-end 137b operative on

the ratchet of a rotatable shaft 137c. A contact disc 137d is freely mounted on the rotatable shaft 137c, and is secured to a standard 137e. A solenoid 137f is arranged to actuate the arm 137a, and to place the pawl-end 137b in position for engagement with the ratchet for rotating the shaft 137c a step, under the influence of return spring 137g, when the solenoid is de-energized. The contact disc 137d is provided with contact points, indicated 1, 2, 3, and 4, respectively, disposed in mutually spaced relation about the marginal edge portion thereof, and a resilient contact finger 137h is fixed to the shaft 137c with its free end arranged to contact the several contact points on the contact disc, in succession, as the shaft rotates in steps. The switch 137 is a well-known standard type and, per se, constitutes no part of the invention. It embodies a spring mechanism (not shown) for rotating the shaft 137c back to starting position, wherein the contact finger rests against contact point #1, when release arm 137i is pulled by its cord 140.

The double step switch 138 is similar to the above described single step switch 137—being also of well-known standard type—except for the fact that two contact discs, indicated 138d and 138dd in Fig. 11, are mutually spaced apart on the rotatable shaft 138c and are individually secured to a standard 138e, and, further, for the fact that its throw arm 138a, through the pawl-end 138b acting on its ratchet, causes shaft 138c to rotate when the solenoid 138f is energized, rather than when the return spring 138g functions, as in the case of single throw switch 137. Resilient contact fingers 138h and 138hh are individually fixed to the shaft 138c, and press against the contact points of their respective contact discs as the shaft rotates a step at a time. The contact points of the respective contact discs 138d and 138dd are indicated 0, 1, 2, 3, and 4, respectively, there being the #0 contact points additional to the #'s 1, 2, 3, and 4 contact points of switch 137. Release arm 138i is arranged to be pulled by cord 141 for the same purpose as specified with respect to switch 137.

Contact finger 137h of the single step switch is electrically connected in the circuit governed by stationary contact 136d of double keying relay 136, while contact finger 138h of the double step switch is electrically connected in the circuit governed by the stationary contact 136c. The contact points 1, 2, 3, and 4 of single step switch 137 are connected, respectively, to the respective character cam solenoids 16, or 1C, 2C, 3C, and 4C; and the contact points 1, 2, 3, and 4 of the first switch disc 138d of the double step switch 138 are connected, respectively, to the respective space cam solenoids 19, or 1S, 2S, 3S, and 4S, the contact point #0 thereof being a blank. Accordingly, when arm 136a of the double keying relay is held against upper stationary contact 136c by the force of spring 136e just prior to commencement of operation of the machine, the resilient contact finger 137h of the single step switch being held against #1 contact point and the resilient contact fingers 138h and 138hh of the double step switch being held against #0 contact points, as illustrated in Fig. 13, no current flows through the machine from the battery or other power source P. But when a signal is received at 134 and is relayed, through keying relay 136, to the main keyed circuit of the machine, each of the solenoids 136f, 137f, and 138f of the double keying relay 136, single step switch 137, and double step switch 138, respectively, is ener-

gized, so that the throw arm of the double keying relay carries its contact 136b against stationary contact 136d, the throw arm of the single step switch carries its pawl-end 137b upward, against the tension of return spring 137g, placing it ready for action against its ratchet for rotating shaft 137c one step, and the throw arm of the double step switch carries its pawl-end 138b downward, against the tension of return spring 138g, forcing rotation of its ratchet, and, therewith, shaft 138c, one step, and causing resilient contact fingers 138h and 138hh to move from their associated contact points #0 to their associated contact points #1, all simultaneously and at the first instant of the received signal.

During the duration of the signal, current from the power source P flows through #1 contact point of the single step switch 137 and causes rotation of the character cam of the first CS translating unit a distance which is directly proportional to the time length of the received signal. Meanwhile, no current flows through double step switch 138—even though its contact fingers are pressed against their respectively associated #1 contact points—because its circuit is broken at the double keying relay 136.

When this first received signal is ended, the rest, i. e., space, which follows, breaks the main keyed circuit at relay 135, and de-energizes the aforesaid solenoids 136f, 137f, and 138f, simultaneously. Thus, movable contact 136b of the double keying relay again makes with the upper stationary contact 136c, pawl-end 137b of the single step switch causes contact finger 137h to advance one step to its associated #2 contact, and pawl-end 138b of the double step switch rises into position, relative to its associated ratchet, to advance the contact fingers 138h and 138hh, each a further step, upon the reception of a subsequent signal, all simultaneously and at the first instant of the rest (space).

During the duration of the rest (space), current from the power source P flows through the #1 contact point of the first disc, 138d, of the double step switch, and causes rotation of the space cam of the first CS translating unit a distance which is directly proportional to the time length of the rest (space). Meanwhile, no current flows through single step switch 137—even though its contact finger rests against its associated #2 contact point—because its circuit is broken at the double keying relay 136.

The resilient finger 138hh of the second switch of the double step switch 138 is also pressed against its associated #1 contact during the period of this rest (space), but it is electrically connected in circuit with the solenoid 84, or L, associated with the letter cam 81; and #s 1, 2, 3, and 4 of its associated contact points are respectively connected with the letter cam switches 74 of the respective space cams 1S, 2S, 3S, and 4S. Accordingly, current flows through, and energizes, the solenoid 84 or L, and, thereby, causes the letter cam 81 to rotate, when the space cam 11 of the first CS translating unit travels far enough to trip its associated letter cam switch 74.

It should be here noted that each space cam holds its associated letter cam switch, 74, closed even after it has tripped its associated limit switch and has come to a stop. Therefore, the letter cam 81 continues to rotate until it either opens its own limit switch 97, or until its solenoid is de-energized, when the next signal is received, and breaks the circuit at the double keying relay 136.

If there are no further signals necessary to complete the particular letter, or other symbol being received, the letter cam 81 will rotate until it closes, first, the word cam switch 95, second, the printing switch 96, and, then, finally, until it opens its own limit switch 97. Meanwhile, the character and space cams 10 and 11, respectively, of the first CS translating unit are held fixed in the respective relative positions to which they had previously rotated, and their associated switch pins, 61 and 62, register the particular signal received, whether it be a dot or a dash, on the form plate solenoids 1X and 1Y, respectively. If the signal is a dot, the switch pin 61 makes contact, while 62 does not, and the solenoid 1X is energized. If the signal is a dash, the switch pin 62 makes contact, while 61 does not, and the solenoid 1Y is energized. Thus, the form structure is patterned according to the nature of the signal received.

When the letter cam 81 closes the word cam switch 95, the coil 151 of a magnetic relay, MR, is energized, and the arm 152 is pulled down into contact with stationary contact arm 153. Thereupon, a circuit is completed to the word cam solenoid 83, or W, which keeps the same energized regardless of whether the word cam switch 95 is closed or not. Once the magnetic relay MR is closed, it remains closed until another signal is received by the apparatus and the double keying relay 136 breaks the contact at 136c.

When the letter cam 81 closes the printing switch 96, solenoid 117 is energized, and its plunger 119 is moved rapidly downwardly, causing a rapid descent of the templates 103, as described hereinbefore, so that the particular letter determined by the form structure, patterned in the manner aforescribed, is printed by the typewriter T.

During this period, the word cam 80 is rotating, and, if not stopped because of the reception of another signal by the apparatus, and the consequent breaking of the circuit at 136c of the double keying relay 136, it will complete its normal travel and will close the word spacing switch 94, which energizes solenoid 125, or SB, meaning space bar, and, thus, will cause the space bar 126 of the typewriter to be pulled downwardly. On the bottom of the downward stroke of the space bar 126, the depending pin 127 opens switch 128, which opens the magnetic relay MR, and, thus, de-energizes the solenoid 83, or W, of the word cam.

Release mechanism

It should be remembered that neither the letter cam 81 nor the word cam 80 have friction brake devices associated therewith, such as those aforescribed in connection with the character and space cams, although they do have associated therewith spring-return devices. Accordingly, as soon as the de-energization of either the letter cam solenoid 84 or the word cam solenoid 83 releases the respective associated clutch mechanism, the letter cam 81 or the word cam 80, whichever the case may be, is returned immediately to its initial position by the action of its associated spring 91 acting through its cord 90.

So far as the return of the character and space cams, of the respective CS translating units, is concerned, however, it is necessary to provide means for releasing the friction brake mechanisms at appropriate times in order to return such character and space cams to their initial positions.

To this end, an alternator device 150 is provided. It comprises a solenoid 150a having its plunger articulatively secured to a pivoted arm 150b which has a pawl-end 150c operatively associated with a ratchet 150d fixed to a rotatable shaft 150e. An alternator disk 150f, having alternate contact points, here indicated as black and white, respectively, is mounted on rotatable shaft 150e, but is fixed against rotation by secured to the standard 150g. A resilient contact finger 150h is fixed to shaft 150e, so that its free end travels from contact point to contact point as the shaft rotates, in steps, under the influence of a spring 150i and after solenoid 150a has placed arm 150b in actuating position.

Electrically associated with the above described alternator mechanism 150, is a so-called ratchet release timer, indicated RRT in Fig. 11. It comprises two pendant switch arms 155 and 156, see especially Figs. 13 and 14, journaled on the stub shafts 157 and 158, respectively, which project from opposite lateral ears of a standard 159. Movable contact points 160 and 161 are rigidly mounted on pendant arms 155 and 156, respectively, in such manner that they extend inwardly toward each other from opposite sides of a stationary contact point 162, which they both normally contact when hanging pendant. The two arms are connected by a spring 163 in order to insure good contact of the respective movable contact points 160 and 161 with the stationary contact point 162 when the arms are in their normal pendant positions.

Between the two pendant switch arms 155 and 156, and adjacent their lower ends, a short shaft 164 extends through the standard 159, for rotation, and for lengthwise sliding movement. A cam 165 is rigidly mounted on that end of shaft 164 which lies between the two pendant switch arms 155 and 156, the stated cam being operative to move the respective switch arms outwardly, alternately, as it rotates.

It will be remembered that the rocker arms 55, 55, of each CS translating unit are fixed to the rotatable rocker shafts 56, 56, respectively, such shafts extending longitudinally along the framework within which the CS translating units and the WS unit are mounted; also, that rotation of the respective rocker shafts toward each other will cause the respective rocker arms to release the friction brakes associated with the space and character cams.

One of these rocker shafts 56 projects beyond the end frame piece 36, see Fig. 10, and has freely mounted at its projecting end portion, an arm 166 which extends into side-by-side abutment against the free end of shaft 164. A cap 167 is pinned to the end of short shaft 164, and a coil spring 168 encircles such short shaft, being secured to cap 167, and abutting against standard 159. A rocker arm 169 is fixed to the projecting end of rocker shaft 56, and is resiliently tied to the arm 166 by means of a short spring 170.

The drive shaft 40 from the speed reducer 39 extends through standard 159, adjacent the projecting end portion of shaft 56, and, also, through a second standard 171. On its projecting terminus is fixed a gear 172, which is in mesh with a considerably smaller gear 173. The gear 173 is fixed to one end of a short shaft 174, journaled in the upper portion of standard 171, and effects rotation thereof from drive shaft 40. Fixed to the other end of short shaft 174 is an enlarged hub 175, to whose outer end face is se-

cured a clutch leather 176, or other suitable friction gripping means. Short shaft 174 is so arranged that the outer end face of its hub 175, and, thus, of its clutch leather 176, is directly opposite the outer end face of the drum 165a of cam 165. Accordingly, when that one of the pair of shafts 56 having the projecting end upon which the arms 166 and 169 are mounted, is rotated clockwise from the standpoint of Fig. 13, rocker arm 169 resiliently pulls floating arm 166 against the cap 167 of the movable short shaft 164, and slides such movable short shaft toward the short shaft 174 so that clutch leather 176 engages drum 165a of the cam 165. Since drive shaft 40 is constantly rotating, cam 165 rotates whenever, and as long as, its drum is engaged by the clutch leather 176.

Each shaft of the pair of rocker shafts 56 projects beyond the frame end standard 35 at the other end of the machine from that above discussed, and has fixed to its projecting end a pinion 180. The pinions 180 are in mesh with the respective racks 181, 181 disposed along opposite lateral edges of the carriage 182. A horizontally disposed arm 183 secured at one end to the plunger of a solenoid 184 (or RR, meaning ratchet release), is fixedly attached, at its other end, to the carriage 182, so that, when the solenoid is energized, the carriage is lowered against the force of return spring 185, the latter engaging and acting between the arm 183 and an upper bracket 186, see Fig. 1. Lowering of the carriage 182 rotates rocker shafts 56, 56—one clockwise and the other counter-clockwise—and, thus, through the medium of the several rocker arms 55, 55, associated with the character and space cams of the respective CS translating units, releases the aforescribed friction brakes operative on such character and space cams. Through the medium of the aforescribed ratchet release timer, it also makes and breaks contact between the pendant arm contacts 160 and 161 and their common stationary contact 162. Upper and lower yoke pieces 187 and 188, respectively, each secured to the frame end standard 35, serve to hold carriage 182 in place and, in a measure, guide its movements.

The resilient contact finger 150h of the alternator mechanism 150 is directly electrically connected in circuit with the power source, indicated on the drawings as such. Those alternate contact points of the alternator contact disk 150f which are indicated as white are mutually electrically interconnected, one with another and with the swinging contact 160 of pendant arm 155 of the ratchet release timer, while those alternate contact points indicated as black are mutually electrically interconnected, one with another and with the swinging contact 161 of swinging arm 156. Accordingly, as the ratchet 150d of the alternator is advanced step by step, by the alternate energizing and deenergizing of solenoid 150a, thus rotating shaft 150e step by step so that contact finger 150h contacts first a white and then a black contact point, etc., or vice versa, the pendant arms of the ratchet release timer RRT are similarly swung, so that the entire apparatus is reset to initial position immediately after solenoid 117 causes a letter, or other symbol, to be printed.

Operation

The operative characteristics of the various component mechanisms of the apparatus, both individually and as an assembled whole, are thor-

oughly explained hereinbefore. It remains only to present a correlated picture of the timing of the apparatus as a whole.

Referring now to Fig. 18, which diagrammatically illustrates the time periods of operation of the respective parts of the apparatus in terms of received code signals spelling out the word "New" and commencing the word "York," and referring also to Fig. 19, which diagrammatically illustrates the respective positions of the component cams of the several CS translating units and of the WL timing unit during this period of operation, it is seen that, for the initial letter "N," the character cam of the ICS unit rotates through 3X degrees in three units of time, corresponding to a dash signal, and comes to rest. The therewith associated space cam rotates through 2X degrees in one unit of time, corresponding to a rest or space between individual signals, and comes to rest after tripping its associated letter cam switch and own limit switch. Before the letter cam is effective in its rotation, however, the reception of the dot signal, which, with the aforesaid dash signal makes up the letter "N," breaks the letter cam circuit, allowing the letter cam to return to its initial position. The dot signal is recorded by the character cam of the 2CS unit, which rotates through X degrees more or less, in one unit of time, more or less, followed by rotation of its associated space cam through the standard 2X degrees, in one unit of time, and the consequent tripping of the letter cam switch and space cam limit switch associated with that space cam. This time, however, because no subsequent signal was forthcoming after the standard rest period of one unit of time, the letter cam continues to rotate until it trips, first, the word cam switch, which starts the word cam rotating, second, the printing switch, which causes the letter "N," in accordance with the received signals, to be typed out, and third, its own limit switch. It should be noted that the letter is typed out immediately after the passage of two units of time, see Fig. 18. Meanwhile, the word cam rotates, and continues to rotate until, immediately following the passage of the third unit of time—during which time period the entire machine is reset into its initial position—the signal representing the letter "E" is received by the machine. Since the entire machine had been reset during this third unit of time, the dot signal, representing the letter "E," is received by the character cam of the ICS translating unit (see Fig. 19), rather than the character cam of the 3CS unit, as would have been the case had this signal been a third to the group representing the letter "N." Reception of this subsequent signal, representing the letter "E," immediately breaks the word cam circuit, causing the word cam to return to its initial rest position without being effective in its rotation.

The letter "E," in terms of its one dot signal, is mechanically recorded on the machine by the ICS translating unit of the series and is typed out; then the letter "W," in terms of its three signals—a dot followed by two dashes—is mechanically recorded on the machine by the ICS, 2CS, and 3CS translating units of the series, and is typed out, all as above described relative to the letter "N" and the spacing between it and the letter "E." But now, since the three letters typed out comprise, in themselves, the complete word "New," the word cam continues to rotate, after the letter "W" is typed out, until it effects

its purpose, namely, the tripping of the word space switch, causing the space bar of the typewriter to be depressed, and, therewith, the tripping of its own limit switch. The word cam requires two units of time to travel its appointed path. During this time the rest of the machine is completely reset to initial position. During the spacing of the word on the typewriter, the rest of the machine merely waits in its reset position for the next signal to start the character cam of the ICS unit rotating. This occurs, assuming normal sending, five units of time after the preceding signal was received.

The letter "Y" of the next word is represented by four signals, namely, a dash followed by a dot and two dashes. All four of the CS translating units are thus utilized, as illustrated in Fig. 19, for mechanically recording the received signals. Otherwise, operation of the machine is as aforementioned.

As is stated hereinbefore, as many of the CS translating units as desired may be utilized in a single machine. For example, where it is desired that the machine receive the ordinary SOS distress calls of ships at sea, nine of the CS translating units will be required, since it is customary to send the signals comprising the several letters, SOS, without letter spacing. In such instance, appropriate mechanism may be provided for ringing an alarm bell or the like whenever the SOS distress call is received by the machine.

Should the code signals to which the apparatus is responsive be constant and uniform in speed, it is possible to utilize certain of the general structural characteristics of the herein disclosed apparatus to advantage without the provision of all the structural features thereof. For instance, the space cams may be omitted and the character cams and associated switches and switch pins may be so arranged that a dot will be recorded for rotation of the character cam within a given range, and that a dash will be recorded for rotation of the character cam within a given range which is greater than the first mentioned given range, the same holding true, of course, with respect to any physical agencies employed for the same purpose as the character cams.

Automatically regulated system

In order to facilitate operation of the apparatus aforescribed, additional mechanism may be provided for automatically setting the speed regulator R in various positions necessary to accommodate changes in speed of signal transmission occurring during sending of the messages received.

It will be remembered that the regulator R in the aforescribed embodiment of the invention is adapted for manual setting, at various positions throughout its arcuate path of swing, by means of nuts 71, Fig. 2, which are tightened when it is desired to hold the regulator in any given position and which are loosened when it is desired to swing the regulator into some other position ascertained to be proper by an attendant.

In the present automatic embodiment, illustrated in Figs. 20 through 26, a ratchet, or other mechanism for accomplishing a like purpose, is utilized to maintain the speed regulator—here also indicated R—at any given position, and other mechanism is supplied for determining just how far the regulator R is to swing from an initial rest position when a letter, or other symbol, is received by the apparatus.

As illustrated in Fig. 21, the automatically controlled regulator R of the present embodiment is almost identical with the manually controlled regulator R of the aforescribed embodiment.

There are, however, certain additional mechanisms which affect the movement of the regulator R during operation of the machine. Also, the remainder of the apparatus of the present embodiment is identical with the corresponding portions of the aforescribed manually regulated embodiment, excepting for certain additions thereto, and for rearrangements in placement of the letter cam and the word cam, respectively.

15 The structural and operating characteristics of the present automatically regulated embodiment take into account the nature of the continental code. All the letters of the alphabet, excepting two, i. e., "E" and "T," are represented in the continental code by a plurality, (two or more) of signals equally spaced. The two letters "E" and "T" are each represented by one signal standing alone, the "E" by a dot signal, and the "T" by a dash signal.

20 It is desirable that the rest or space between signals of a letter group be made the standard for automatic operation, and, therefore, because the two letters "E" and "T" are each represented by only one signal and have no rest or space in their formation, the first rest or space 25 in any "letter group" of signals is made the standard for the subsequent "letter group" and for anything else received by the apparatus up to the point where a still subsequent "letter group" of signals, containing a rest or space, is received.

In accordance with this premise, reference means are provided for rotation coincidentally with the rotation of the first space cam of the

40 machine, and for a duration equal to the time length of the space or rest which effects rotation of the said first space cam. Thus, although the machine operates during the receiving of a given letter in a manner determined by the speed of 45 transmission of the letter received immediately previous thereto, it is, during that time, set in accordance with the speed of transmission of the letter actually being received, for subsequent operation in accordance with that speed

50 of transmission. If any subsequent letter is an "E" or a "T," the machine operates according to the standard set by the first space or rest of the preceding "letter group" of signals, and continues to so operate until reset by a change in 55 the first rest or space of a subsequent "letter group" of signals.

The additional mechanism required in connection with the speed regulator R in the present automatically regulated embodiment may be supplied at any of those individual bridge members of the regulator R which are associated with a CS translating unit; here, for sake of convenience, such additional mechanism is shown associated with the first CS translating unit.

60 65 As stated above, the letter cam and the word cam are independently positioned in the present embodiment, the word cam is spaced forwardly of the letter cam in series alignment with the CS translating units of the apparatus, and is provided with an individual and independent regulator bridge member, suitably correlated with the remainder of the regulator R, see Fig. 21.

The first CS translating unit and its associated 70 75 bridge member of the regulator R are illus-

trated in Fig. 20, portions identical with corresponding portions of the manually regulated embodiment being broken out.

Referring now specifically to Fig. 20, the bridge member 200 of the regulator R is journaled on short shafts 201, 202 for partial rotation in a forward and backward swinging movement. The short shafts 201 and 202 are fixed in the longitudinal frame members 28, 28 by means of the respective collars 201-1 and 202-2.

Legs 200a and 200b of the bridge member 200 have auxiliary switching mechanism mounted thereon, as described in detail hereinafter, and the leg 200a has an extended hub 200aa upon which is fixed a sprocket wheel 203.

The regulator R is caused to swing forwardly by means of a clutch connection between a power shaft 204 and the bridge member 200, and is caused to swing backwardly to its initial rest position by means of a return spring 205, see Fig. 21, anchored at one end to the framework of the machine and at the other end to a cord 206, which is wrapped about a drum 207—preferably a part of that bridge member 200—1 which is associated with the letter cam of the machine. The spring 205 must be of sufficient strength to swing the entire regulator R, with the exception of the independent bridge member 200—2, which is associated with the word cam, back to initial rest position. A bracket stop 208 determines this initial rest position and serves to halt the regulator in its backward swing. A similar bracket stop 208—1 serves the same purpose for the independently returned bridge member 200—2.

The power shaft 204 may be connected by any suitable and well known flexible drive means, as for instance pulleys and a belt or sprocket wheels and a chain, (not shown) with the drive shaft 40 of gear box 39, see Fig. 1.

The aforesaid clutch connection between the power shaft 204 and the bridge member 200 is here provided by clutch mechanism housed in a box 209, see especially Fig. 24. The clutch mechanism may be of any suitable type. As illustrated, it comprises longitudinally aligned individual short shafts 210 and 211 mounted for rotation in the hubs 209a and 209b, respectively, of the housing 209. A movable clutch disc 212 is slidably mounted on the inner end of short shaft 211, for engagement with a stationary clutch disc 213, pinned to the inner end of short shaft 210. The movable clutch disc 212 is feathered to its shaft by the feather 214, and thus rotates with its shaft at all times. Both the clutch discs are faced with clutch leathers, or the like, and a lever arm 215, fulcrumed to the wall bracket 216, has its short arm 215a bifurcated and yoked by a link connection to the body of movable clutch disc 212, and has its long arm 215b slotted and linked to the plunger of a solenoid 217, mounted within the box 209. Accordingly, when the solenoid is energized, movable clutch disc 212 engages with stationary clutch disc 213.

A sprocket wheel 218 is pinned to the protruding end of short shaft 211, and a chain 219 connects it with the sprocket wheel 220 of power shaft 204. Likewise, a sprocket wheel 221 is pinned to the protruding end of short shaft 210, and a chain 222 connects it with the sprocket wheel 203 of the bridge element 200.

For maintaining the regulator R in its swung position, a ratchet wheel 213a is provided—preferably as an integral part of the stationary clutch disc 213—together with a pawl 223. The pawl 223 conveniently forms the plunger of a solenoid 224, which, when energized pulls the pawl 223 down against the yielding support of spring 225 and, thus, releases ratchet wheel 213a so the regulator R may be returned to its initial rest position by the return spring mechanism aforescribed.

Mechanism is provided for determining how far forwardly the regulator R will swing, on any given swinging movement of same, so it will be positioned properly in accordance with the speed of transmission of signals being received by the machine. Such mechanism comprises a swinging arm 230, pivoted for limited swinging movement on the short shaft 201, and a second swinging arm 231, pivoted for limited swinging movement on the short shaft 202.

The swinging arms are headed at their free extremities to provide enlarged switch-tripping members 230a and 231a, respectively. They have elongated hub portions 230b and 231b, respectively, upon which are mounted sprocket wheels 232 and 233, respectively. They are driven from the power shaft 204 by clutch connections similar to that aforescribed, and illustrated per se in Fig. 24.

The clutch mechanisms which provide the clutch connections are housed in respective boxes 234 and 235, see Fig. 20. A sprocket wheel 236, associated with the movable clutch disc of box 234, is connected with a sprocket wheel 237 of power shaft 204 by means of the chain drive 238, and a sprocket wheel 239, associated with the movable clutch disc of box 235 is connected with a sprocket wheel 240 of power shaft 204 by means of a chain drive 241. Likewise, a sprocket wheel 242, associated with the stationary clutch disc of box 234, is connected with the sprocket wheel 232 of the swinging arm 230 by means of a chain drive 243, and a sprocket wheel 244, associated with the stationary clutch disc of box 235, is connected with the sprocket wheel 233 of the swinging arm 231 by means of a chain drive 245.

As in the clutch mechanism of Fig. 24, a solenoid—here 246—serves to engage the clutch mechanism in box 234, and a second solenoid—here 247—serves to release the ratchet which holds sprocket wheel 242 against return rotation. Also, a solenoid 248 serves to engage the clutch mechanism in box 235, and a second solenoid 249 serves to release the ratchet which holds sprocket wheel 244 against return rotation.

The sprocket wheels 242 and 244, together with their respectively connected sprocket wheels 232 and 233, carry their respective swinging arms 230 and 231 to initial rest positions under the influences of respective return spring mechanisms, indicated generally 250 and 251, when the respective ratchets are released as just described. The return spring mechanisms 250 and 251 are similar to the return spring mechanisms described hereinbefore, each embodying a spring anchored at one end, and being secured at the other end to a cord wrapped around a drum formed on the hub of the particular swinging arm with which it is associated. Limit stops 252 and 253, see Fig. 25, are provided for determining the initial rest positions and the return positions of the respective swinging arms 230 and 231.

Mechanism is provided for determining how far forwardly each of the swinging arms 230 and 231 should move in any given swinging movement of same, so that one or the other of them will be

positioned in accordance with the location to which it is desired to place the regulator R at any given moment. Such mechanism comprises a swinging switch-arm 255 pivoted for limited swinging movement on the short shaft 281, and a second swinging switch-arm 256 pivoted for limited swinging movement on the short shaft 282. The switch-arms 255 and 256 carry respective switches, indicated generally 257 and 258, which are normally closed, but which have resiliently urged, slidably switch pins 251a and 258a, respectively, protruding into the paths of swing of the respective switch-tripping arms 230 and 231 for actuation by the switch-tripping heads 230a and 231a thereof.

The swinging switch-arms 255 and 256 move simultaneously with each other and simultaneously with the movement of the space cam 11 of the ICS translating unit with which they are associated, and, also, simultaneously with the movement of the regulator R. The swinging arms 230 and 231, however, move alternately, one with the other, and at a rate of movement which is considerably faster than the rate at which the swinging switch-arms and the said space cam move. The regulator R also swings forwardly at a considerably more rapid rate than do the switch-arms 255 and 256 and the said space cam.

The swinging switch-arms 255 and 256 are driven, like the regulator R and the swinging arms 230 and 231, by clutch connections with the power shaft 204. Clutch mechanisms, similar to that illustrated per se in Fig. 24, are provided in the boxes 259 and 260, respectively. A sprocket wheel 261, associated with the movable clutch disc of box 259, is connected to a sprocket wheel 262 of power shaft 204 by means of a chain drive 263. Likewise, a sprocket wheel 264, associated with the movable clutch disc of box 260, is connected with a sprocket wheel 265 of power shaft 204 by means of a chain drive 266. Also; a sprocket wheel 267, associated with the stationary clutch disc of box 259, is connected with a sprocket wheel 268 of the swinging switch-arm 255 by means of a chain drive 269, and a sprocket wheel 270, associated with the stationary clutch disc of box 260, is connected with a sprocket wheel 271 of swinging switch-arm 256 by means of a chain drive 272.

As in the previously described clutch mechanisms, a solenoid 273 serves to engage the clutch mechanism of box 259, and a solenoid 274 does likewise for the clutch of box 260. Also; a solenoid 275 serves to release the ratchet of the stationary clutch disc of box 259, allowing switch-arm 255 to return to its initial rest position against limit stop 252, and a solenoid 276 serves to release the ratchet of the stationary clutch disc of box 260, allowing switch-arm 256 to return to its initial rest position against limit stop 253.

Return spring mechanisms, indicated generally 277 and 278 and similar in construction to the aforescribed return spring mechanisms, are associated with the switch-arms 255 and 256, respectively, for returning them to initial positions.

A limit switch is provided for the switch-arms 255 and 256 to define a maximum extent of rotation, see switch 291, Fig. 26.

In order to forwardly swing either the arm 230 or the arm 231, whichever the case may be in any given moment of operation of the machine, considerably faster than the switch-arms 255 and 256, the sprocket wheels 237 and 240 are made larger in a predetermined suitable ratio than the sprocket wheels 262 and 265, the latter two being

equal in size. Likewise for the regulator R; in order to swing it forwardly into position at a high rate of speed the sprocket wheel 220 is made of a greater diameter than are the sprocket wheels 262 and 265.

Since the switch arms 255 and 256 always move in unison, it would be entirely possible, in certain constructions of the machine, to mount them securely on a common, transversely extending shaft 10 for rotation therewith, and, thus, to eliminate duplicate clutch, release, and return mechanisms together with their necessary duplicate solenoids.

As aforesaid, the additional switch mechanism for this automatically regulated embodiment is 15 associated with only the first bridge member 200 of the regulator R. The other bridge members, indicated 200a, 200b, and 200c, and associated with the remaining CS translating units, are interconnected with the first bridge member 200, 20 and with the bridge member of the letter cam, by means of longitudinal connecting links 279. Independent bridge member 200-2 is associated with the word cam of the machine.

The independent bridge member 200-2 is illustrated per se in Fig. 22; the word cam is indicated therein by dotted lines. The bridge member 200-2 has legs 200-2a and 200-2b which are respectively pivoted for swinging movement on short shafts 280 and 281, such short shafts being 30 fixed in the frame elements 28, 28 by means of collars 280-1 and 281-1.

A ratchet wheel 282 is mounted for rotation on the projecting end of short shaft 280, and is secured to the leg 200-2a of bridge member 200-2. 35 A pawl 283 is arranged on a stub shaft, extending from the adjacent frame element 28, for release by means of a solenoid 284, and for re-engagement by means of a return spring 285.

The bridge member 200-2 swings in unison 40 with the remainder of the regulator R, but is arranged to return to initial rest position independently. To this end, a hub 286 is mounted for free rotation on the projecting end of short shaft 281, and has an upstanding finger 286a 45 projecting therefrom. A sprocket wheel 287 is fixed to the hub 286 and is connected with the sprocket wheel 207 of bridge member 200-1 by means of a chain drive 288. A lug 289 projects outwardly from the leg 200-2b into the path 50 of rotation of the finger 286a. Accordingly, when finger 286a is swung forwardly by reason of the connection between the sprocket wheels 207 and 287, it abuts against lug 289 and swings bridge member 200-2 forwardly in unison with the 55 movement of the several bridge members of the regulator R.

Because of the ratchet provided by the ratchet wheel 282 and pawl 283, the bridge member 200-2 is not returned to its initial rest position 60 with the return of the other bridge members of the regulator R. For independently returning bridge member 200-2 to its initial rest position when actuation of the solenoid 284 releases the ratchet, a drum 290, secured to the leg 200-2b 65 and freely mounted on the short shaft 281, is provided. As in the case of previously described return spring mechanisms, a cord 291 is wrapped around the drum 290 and has its free end secured to an end of a spring 292 whose other end 70 is anchored to the framework of the machine.

Two normally closed switches, indicated generally 295 and 296, are respectively secured to the legs 200a and 200b of the bridge member 200, and have resiliently mounted throw pins 75 295a and 296a protruding into the paths of swing

of the switch-tripping heads of swinging arms 230 and 231, respectively. The switches are tripped, and, thus, opened, when their throw pins are pushed backwardly, against the urge of their resilient mountings, by pressure contact therewith of the said switch-tripping heads of swinging arms 230 and 231.

Fig. 26 represents a wiring diagram appropriate to the additional requirements of the automatically regulated system. It illustrates, diagrammatically, additional electric equipment and wiring connections employed with the additional mechanism of the present automatic embodiment, and should be considered in connection with the wiring diagram of Fig. 11.

With this in mind, and referring now to both Fig. 11 and Fig. 26, it will be seen that the electrical system of the automatically regulated embodiment is tied in closely with the electrical system aforesaid relative to the manually regulated embodiment. Connections for the electrical system of Fig. 26 are made with the wiring of the first space cam 1S, and with the wiring of the second character cam 2C, as hereinafter more fully explained. Connections are also made with the wiring of the ratchet release mechanism RR and the ratchet release timer RRT, as well as with the wiring of the double keying relay 136. Otherwise, the electrical system of Fig. 11 remains substantially unchanged.

At the commencement of operation of the apparatus, either one or the other of the swinging arms 230 and 231 is in some forwardly swung position. This ordinarily occurs by reason of operation of the device at some previous time, but, in the case of a new installation, may be due to a deliberate setting of the same in some position corresponding to a usual speed of signal transmission. It should be noted that during the course of operation of the apparatus, these swinging arms 230 and 231 determine the various positions which the speed regulator R will assume in compensating for variations in speed of transmission of the received signals.

Under the above circumstances, the regulator R lies in its initial rest position, as indicated in Fig. 21 by dotted lines. The switch-arms 255 and 256 are in their initial rest positions, as is, also, that one of the swinging arms 230 and 231 which is not in a forwardly swung position. The character and space cams of the CS translating units, and the letter and word cams of the WL timer unit, are, of course, all at their initial rest positions.

When a signal is received, and the arm of double keying relay 136 makes electrical contact with the lower contact point 136d, the character cam 10 of the first translating unit, i. e., 1CS, immediately commences to rotate in the manner aforescribed with respect to the manually regulated embodiment. During this period, current flows through the release solenoid 284 of the independent bridge member 200-2, associated with the word cam, to insure that such bridge member is in its initial rest position. No current, however, flows through the remainder of that portion of the electrical system illustrated in Fig. 26 until the signal ceases and the double keying relay 136 makes contact with its upper contact point 136c. The character cam 10 then comes to an abrupt halt and its associated space cam 11 immediately commences to rotate.

In order to orient the additional wiring diagram of Fig. 26 with the base wiring diagram of

Fig. 11, the letters A, B, D, and E have been placed in both figures to indicate the major points of interconnection of the two systems, whereby they form an integrated and operative whole.

- 5 It can be seen that the solenoid 1S, operative on the space cam of the first CS translating unit, the solenoid 217, operative on the clutch mechanism in box 209 associated with the speed regulator R, and the solenoids 273 and 274, operative on the clutch mechanisms in boxes 259 and 260, respectively, associated with the switch-arms 255 and 256, respectively, are all electrically connected in parallel. Accordingly, when the double keying relay makes contact with upper contact point 136c, thus completing the circuit which actuates the space cam 11, the several solenoids connected in electrical parallel with the solenoid 1S of the space cam 11 will be actuated simultaneously therewith.
- 10 The switch-arms 255 and 256 are geared to move at a speed approximately that of the space cam 11, but, as mentioned hereinbefore, the speed regulator R is geared to move at a considerably faster rate. The speed regulator R, therefore, swings forward rapidly until either the switch 295 or the switch 296 thereof is tripped by pressure contact against the switch tripping head of that one of the swinging arms 230 and 231 which is in the forwardly swung position, and the space cam 11 and the switch-arms 255 and 256 follow at their slower rate until the reception of another signal by the machine breaks the circuit through double keying relay 136, it being understood, of course, that power shaft 204 is constantly rotating during use of the machine. When there is a change in speed of signal transmission, the space cam may be halted earlier by tripping its own limit switch 14, located on bridge member 200 of the previously halted regulator R, but, in this case, the switch-arms continue to swing forwardly for the full duration of the rest or space, thus measuring out the time length of that rest or space in terms of angular degrees of rotation.
- 15 The switches 295 and 296 are electrically connected into the space cam solenoid circuit through the alternator disc 300-2 of a triple alternator 300. The triple alternator 300 (illustrated diagrammatically in Fig. 26) comprises three alternator discs 300-1, 300-2, and 300-3 all mounted on a single shaft for rotation therewith. The shaft is rotated step by step by means of a solenoid 301 acting on a ratchet arrangement, indicated generally 302, the solenoid being electrically connected in parallel with the solenoid 2c, associated with the character cam of the second CS translating unit, i. e., 2CS, for a reason fully explained hereinafter.
- 20 The contact points of alternator disc 300-2 are electrically connected with the switches 295 and 296, alternately, as indicated black and white, while the resilient contact finger is electrically connected into the main space cam solenoid circuit. Until the regulator R swings forward sufficiently to allow bridge member 200 to trip one or the other of its switches 295 and 296 on the switch tripping head of that one of the swinging arms 230 and 231 which is in "swung" position, both of such switches are closed, although current can pass through only the one which is in circuit with the correct set of contact points of the alternator disc 300-2, either the black or the white depending upon which the resilient contact finger is against. The setting of the machine is such, however, that current flows through

that one switch which is due to be tripped by that one swinging arm which is in "swung" position. When that one switch is tripped by such swinging arm, the circuit through solenoid 217 is broken and the regulator R is abruptly halted, as by reason of the frictional pressure of ratchet pin 223, or by any other suitable braking means, which may be additionally supplied.

The speed regulator R is now positioned in accordance with a predetermined speed setting, or in accordance with the speed of transmission of a "letter group" of immediately preceding signals, and the machine thereafter operates as explained with respect to the manually regulated embodiment during the remainder of the presently received "letter group" of signals, as well as during the reception of the letter "E" and the letter "T" if either or both follow immediately after said presently received "letter group" of signals.

As stated hereinbefore, the switch-arms 255 and 256 swing forwardly during the entire time period of the rest or space, whether or not the space cam is halted earlier by tripping its own limit switch 74. They, therefore, provide a record of the time length of the initial rest or space of the "letter group" of signals presently received, so that the speed regulator R may be correctly set for the subsequent "letter group" of signals.

When a subsequent signal is received by the apparatus, and the consequent dropping of the arm of double keying relay 136 into contact with its lower contact point 136d starts the character cam of the second CS translating unit, i. e., 2CS, rotating by energization of its solenoid 2C, that one of the swinging arms 230 and 231 which has been at its initial rest position during the period of operation above described, swings into the position marked by the switch-arms 255 and 256 and abruptly halts. The switch-arms are returned to initial rest position at the time the ratchet release solenoid 184, or RR, resets the entire machine.

By referring to the wiring diagram of Fig. 26, it will be seen that switches 257 and 258 of the switch-arms 255 and 256, respectively, are electrically connected in circuit with the solenoid 2C of the character cam of the second CS translating unit through the medium of alternator disc 300-1 of the triple alternator 300, the switch 257 being connected to the set of white contact points of the alternator disc, and the switch 258 being connected to the set of black contact points. The resilient contact finger of the alternator disc is connected into the circuit of solenoid 2C, as is, also, solenoid 301 of the ratchet arrangement 302 which rotates the triple alternator step by step.

Accordingly, when the reception of a second signal by the apparatus sends current through the circuit of solenoid 2C, current will flow through the alternator 300-1, and will also energize solenoid 301, placing the pawl of ratchet 302 in position to rotate the triple alternator 300 one step when the solenoid is de-energized.

Since the switches 257 and 258 are normally closed, current flows through the one which is connected by reason of the particular setting—black or white—of the alternator 300-1, and since the electrical connections of the respective switches 257 and 258, relative to the black and white contacts of alternator disc 300-1 are opposite to the electrical connections of the respective switches 295 and 296, relative to the black and white contacts of alternator disc 300-2, current will flow through that one of the switches which

corresponds to the swinging arm (230 or 231) which is at initial rest position.

Switches 257 and 258 control the flow of current to solenoids 246 and 248, respectively, in clutch boxes 234 and 235, respectively, arranged to engage the swinging arms 230 and 231, respectively, with the power shaft 204 for actuation thereby.

Therefore, when current flows through the circuit of solenoid 2C, that one swinging arm (230 or 231) which is at initial rest position swings forward rapidly until its switch-tripping head (230a or 231a) opens its corresponding switch (257 or 258) on its corresponding switch-arm (255 or 256), whereupon it is abruptly halted. That one swinging arm is, therefore, now set in a position corresponding to the time length of the initial rest or space of the "letter group" of signals presently received, and stands ready to halt the speed regulator R at the proper position for the initial rest or space of the "letter group" of signals received immediately subsequently.

On the rest or space which immediately follows the second signal in the said presently received "letter group" of signals, solenoid 301 is de-energized, and the ratchet mechanism 302, under the influence of its return spring, advances the triple alternator one step from black to white, or vice versa, depending upon the particular electrical hook-up of the machine.

It should be here noted that should the single signal representing the letter "E," or the single signal representing the letter "T," follow any "letter group" of signals, the solenoid 301 would not be energized and the triple alternator would not be advanced until the next full "letter group" of signals. Under these circumstances, the particular swinging arm (230 or 231) which is in 40 forwardly swung position will remain in that position during the reception of the letter "E" or the letter "T" by the machine. Only when a subsequent "letter group" of signals is received, will the swinging arms 230 or 231 resume their normal 45 alternating sequence of operation.

The release solenoid 224—associated, in clutch box 209, with the clutch mechanism for driving the speed regulator R; the release solenoid 275—associated, in clutch box 259, with the clutch mechanism for driving the switch-arm 255; and the solenoid 276—associated, in clutch box 260, with the clutch mechanism for driving the switch-arm 256—are all electrically connected in parallel with the release solenoid 184, or RR, 55 and, consequently, serve to release their respective ratchets and associated mechanisms at the same time the machine as a whole is released and returned to initial rest position.

The release solenoid 247—associated, in clutch box 234, with the clutch mechanism for driving the swinging arm 230; and the release solenoid 249—associated, in clutch box 235, with the clutch mechanism for driving the swinging arm 231—are, however, electrically connected into the circuit of release solenoid 184, or RR, through the medium of the alternator 300-3 of the triple alternator 300, the release solenoid 247 being here shown connected to the set of white contact points, and the release solenoid 249 to the set 70 of black contact points. Accordingly, only one of the swinging arms 230 and 231—that one which has already fulfilled its appointed task of halting the speed regulator R at proper position—is returned to initial rest position with the machine as a whole after a "letter group" of signals

has been received. The other remains in its forwardly swung position to fulfill its appointed task of halting the speed regulator R in proper position for the next "letter group" of signals.

It should be understood, of course, that this automatic feature, above described, need be employed with the basic construction only if and when it is deemed necessary or advantageous.

While this invention is specifically illustrated and described with respect to only certain structural forms and embodiments thereof, it should be clearly understood that many changes in the said certain structural forms and embodiments may be made, and many other structural forms and embodiments may be developed by others skilled in the art, without departing from the spirit and generic purview of the invention set forth herein and in the following claims.

I claim:

1. In code controlled apparatus having code receiving means and a signal permutation device for storing up received code signals so that said code can be made to effect a desired end result, an intermediate device arranged for actuation by a received code signal, and, thereafter, by the immediately following code space for establishing a comparative relation between said received code signal and said thereafter immediately following code space; comparing means associated with said intermediate device, said comparing means being responsive to both the code signal actuation of said intermediate device and the code space actuation thereof and effective to compare the two, one with the other; and means responsive to said comparing means and associated with said signal permutation device for variably setting said signal permutation device in accordance with the comparative relations between received signals and the respective thereafter immediately following received spaces.

2. In code controlled apparatus having code receiving means and a signal permutation device for storing up received code signals so that said code can be made to effect a desired end result, an intermediate device comprising means arranged for actuation by a received code signal, and a second means associated with the first-named means and arranged for actuation by the immediately following code space, said first and second named means being effective to establish a comparative relation between said received code signal and said thereafter immediately following code space; comparing means associated with said intermediate device, said comparing means being responsive to both the code signal actuation of said intermediate device and the code space actuation thereof and effective to compare the two, one with the other; and means responsive to said comparing means and associated with said signal permutation device for variably setting said signal permutation device in accordance with the comparative relations between received signals and the respective thereafter immediately following received spaces.

3. Code controlled apparatus, comprising a series of pairs of associated, but mutually independent, physically responsive means, one means of each of said pair of means being arranged for actuation by a respective code signal and the other means of each of said pair of means being arranged for actuation by a respective code space which immediately follows the said respective code signal; respective control means common to both physically responsive means of each of said pairs of the said series, said control means

being each operable to produce one or the other of two predetermined unitary actions depending upon the comparative degrees of actuation of the physically responsive means of the pairs of physically responsive means with which they are respectively associated; and adjustable regulator means mutually correlating the said pairs of physically responsive means.

4. Code controlled apparatus, comprising a series of pairs of associated, but mutually independent, physically responsive means, one means of each of said pair of means being arranged for actuation by a respective code signal and the other means of each of said pair of means being arranged for actuation by a respective code space which immediately follows the said respective code signal; respective control means common to both physically responsive means of each of said pairs of the said series, said control means being each operable to produce one or the other of two predetermined unitary actions depending upon the comparative degrees of actuation of the physically responsive means of the pairs of physically responsive means with which they are respectively associated; adjustable regulator means mutually correlating the said pairs of physically responsive means, and means associated with one of said pairs of physically responsive means for automatically adjusting said regulator means in accordance with the speed of code transmission.

5. In code controlled apparatus, a translating device comprising a pair of independently and rotatably mounted elements substantially aligned axially; means for causing one of said elements to move throughout the duration of a code signal; means for causing the other of said elements to move during the immediately subsequent code space; and a pair of switches mounted on one of said elements and having respective switch actuating pins extending into pressure engagement with a face of the other of said elements, the latter of said elements having its said face contoured in a predetermined manner for tripping one or the other of said switch pins depending upon the comparative degrees of movement of the said elements relative to one another.

6. In code controlled apparatus, a pair of independently mounted but mutually associated elements, electrical relay means for actuating first one and then the other of said elements in accordance with a code signal and a next subsequent code space, respectively, and a pair of electric switch means associated in active cooperation with both elements of said pair of elements, said elements and said electric switch means being so arranged that one or the other of said switch means is actuated, depending upon the comparative degrees of movement of said elements of said pair of elements relative to each other.

7. Code controlled apparatus, comprising an aligned series of code translating devices, means for operating said translating devices successively, from the first on down the line, each by a corresponding code signal and immediately subsequent code space, timing means, adjustable regulator means correlating the respective translating devices and the said timing means, and means for returning the respective devices to their respective starting positions after a given operative cycle of the apparatus.

8. Code controlled apparatus, comprising an

aligned series of code translating devices equivalent in number to the maximum number of symbols in any code symbol group to be handled, means for operating said translating devices successively, from the first on down the line, each by a corresponding code signal and immediately subsequent code space of a single code symbol group, a timing device aligned with said translating devices and disposed at the end of said series, means for operating said timing device to accommodate the code spaces between code symbol groups, adjustable regulator means interconnecting and correlating the said translating devices and the said timing device of said series, and means for returning the respective devices to their respective starting positions after a given operative cycle of the apparatus.

9. Apparatus for translating and printing telegraphic code messages, including, in combination, an aligned series of code translating devices equivalent in number to the maximum number of symbols in any code symbol group to be handled, means for operating said translating devices successively, from the first on down the line, each by a corresponding code signal and immediately subsequent code space of a single code symbol group, a timing device aligned with said translating devices and disposed at the end of said series, means for operating said timing device to accommodate the code spaces between code symbol groups, adjustable regulator means interconnecting and correlating the said translating devices and the said timing device of said series, a selective printing device, means coupling said selective printing device to the said translating devices and the said timing device, and means for returning the respective devices to their respective starting positions after a given operative cycle of the apparatus.

10. A method of converting a telegraphic code message into a desired end result comprising physically recording sequential signals of said message successively in terms of their respective time lengths, and, likewise, successively physically recording the spaces which alternate with said signals; physically comparing each signal, as recorded, with its subsequent space, as recorded; and effecting, by reason of said comparison, a unitary action whose nature depends upon the approximate time length of the particular signal, as recorded, as compared with the approximate time length of its subsequent space, as recorded.

11. In code controlled apparatus, a translating device comprising a pair of elements mounted in substantially axial alignment relative to each other and for independent relative rotation, means for causing rotation of one element of said pair, means for causing rotation of the other element of said pair, a pair of electrical switches mounted on one element of said pair and having respective switch actuating means extending into the path of rotation of the other element of said pair, means associated with the last said other element for tripping either one or the other of said switch actuating means depending upon the relative degrees of rotation of the elements of said pair, and a pair of motive means having the component motive means thereof electrically connected, respectively, with the respective switches of said pair of switches.

12. In code controlled apparatus, a plurality of pairs of code signal responsive means and code space responsive means, said pairs being disposed in series alignment; means for operating

said code signal responsive means in accordance with received code signals; means for operating said code space responsive means in accordance with the spaces between received code signals;

5 individual settable means adapted to be set, respectively, in accordance with the comparative responses of the code signal responsive means and the code space responsive means of the respective pairs thereof; and means for causing said individual settable means to be set, respectively, in accordance with the comparative responses of the code signal responsive means and the code space responsive means of the respective pairs thereof.

10 13. In code controlled apparatus, a plurality of pairs of code signal responsive means and code space responsive means, said pairs being disposed in series alignment; means for operating said code signal responsive means in accordance with received code signals; means for operating said code space responsive means in accordance with the spaces between received code signals; individual settable means adapted to be set, respectively, in accordance with the comparative responses of the code signal responsive means and the code space responsive means of the respective pairs thereof; means for causing said individual settable means to be set, respectively, in accordance with the comparative responses of the code signal responsive means and the code space responsive means of the respective pairs thereof; means for cooperation with said individual settable means, collectively, for producing an action whose nature is determined thereby; and means for actuating said last named means at intervals depending upon said code.

15 14. Code controlled apparatus comprising an aligned series of individual code translating devices; a timing device aligned with said code translating devices at the end of said series; common means for motivating the respective code translating devices and said timing device; individual clutch means respectively associated with the respective translating devices and the said timing device for respectively interconnecting the same with said common motivating means; individual electrically operable means respectively associated with the respective clutch means for respectively causing the interconnection of said individual clutch means with said common motivating means; means for converting code signals and code spaces into respective electrical impulses; means for sequentially directing successive pairs of said electrical impulses to those of said electrically operable means which are associated with said translating devices; regulator means correlating said translating devices and said timing device, said regulator means being adjustable in accordance with the speed of code transmission; individual electrical switch means mounted on said regulator means in association, respectively, with the respective translating devices and the said timing device, those of said switch means which are associated with the translating devices being connected in circuit with the interconnection-causing means of said timing device and being disposed for tripping by said translating devices in effecting operation of said interconnection-causing means; individual settable means adapted to be set, respectively, by operation of the respective translating devices; means associated with said settable means and adapted for cooperation therewith, the said switch means which is asso-

ciated with the said timing device being adapted to initiate operation of the last named means associated with said settable means; and means for returning the apparatus to initial starting position after any given cycle of operation, the said switch means which is associated with the said timing device being adapted to initiate operation of the last named return means.

15. Code controlled apparatus including an aligned series of individual code translating devices, each comprising a pair of cam elements mounted substantially side-by-side for independent movement relative to each other; a timing device aligned with said code translating devices at the end of said series, and likewise comprising a pair of cam elements mounted substantially side-by-side for independent movement relative to each other; means for selectively motivating the respective cam elements of the said code translating devices sequentially in accordance with code signals and code spaces considered in pairs; individual settable means adapted to be set, respectively, in accordance with the comparative movements of the cam elements of the respective code translating devices; means for setting said individual settable means in accordance with the comparative movements of the cam elements of the respective code translating devices; regulator means comprehending all of said code translating devices and said timing device and adapted for adjustment in accordance with the speed of code transmission; individual control means carried by said regulator means and associated, respectively, with the space cam elements of the respective code translating devices, said control means being adapted for actuation by the said space cam elements; effect producing means for cooperation with said settable means, collectively, for producing an effect whose nature is determined by the setting of said settable means; control means carried by said regulator and associated with one cam element of said timing device; control means carried by said regulator and associated with the other cam element of said timing device; the said control means associated with said translating devices being respectively operable to initiate operation of the said one of said cam elements of said timing device, and the control means associated with said one cam element being operable to initiate operation of said effect producing means, as well as to initiate operation of said other cam element of said timing device; another effect producing means; and control means carried by said regulator and associated with said other cam element of said timing device, the last named control means being operable to initiate operation of said other effect producing means.

16. In code controlled apparatus, means movable in response to a received code signal; means movable in response to a thereafter immediately following code space; regulator means movable to a position determined by the movement of the last named movable means, means for marking said position, and automatic means for moving said regulator means to, and in coincidence with, said marked position.

17. In control apparatus, the combination of a primary electrical circuit means; means for keying said primary circuit in accordance with signals impressed upon said keying means; a double-keying relay connected in said primary circuit; a second electrical circuit means arranged to be opened and closed by one set of

contacts of said double-keying relay; a third electrical circuit means arranged to be opened and closed by the other set of contacts of said double-keying relay; double-step switch means connected in said second electrical circuit, each step switch of which has a contact arm and a plurality of alternate contact positions; a plurality of local electrical circuits connected, respectively, with the said alternate contact positions of one step switch of said double-step switch means, and arranged to be opened or closed, respectively, in accordance with the setting of said one step switch; a plurality of local electrical circuits connected, respectively, with the said alternate contact positions of the other step switch of said double-step switch means, and arranged to be opened or closed, respectively, in accordance with the setting of said other step switch; a single-step switch means connected in said third electrical circuit and having a contact arm and a plurality of alternate contact positions; a plurality of local electrical circuits connected, respectively, with the said alternate contact positions of said single-step switch means, and arranged to be opened or closed, respectively, in accordance with the setting of said single-step switch means; electrical actuating means connected in said primary circuit for causing said step switches of said double-step switch means to advance from contact point to contact point, successively and intermittently, as said primary circuit is closed, successively and intermittently, by the keying action of said keying means; electrical actuating means connected in said primary circuit for causing the step switch of said single-step switch means to advance, successively and intermittently, by the said keying action of said keying means; the step switch of said single-step switch means being in initial contact position at the commencement of any given cycle of operation of said control apparatus, and the step switches of said double-step switch means being in non-contact positions, which are immediately behind the initial contact positions thereof, at the commencement of any given cycle of operations of said control apparatus, so they will be advanced into initial contact positions upon energization of the said electrical actuating means associated with the said double-step switch means; a series of devices arranged to be electrically actuated, respectively, and successively and intermittently, in accordance with the successive settings of the step switch of the said single-step switch means; a second, corresponding series of devices arranged to be electrically actuated, respectively, and successively and intermittently, in accordance with the successive settings of the said one step switch of the said double-step switch means, the said two series of devices having their respective devices arranged in pairs, one device from one of said series with the corresponding device from the other of said series; a series of control means corresponding in number to the number of said pairs of devices, and associated with said pairs of devices, in respective order, each of said control means being adapted to respond to the actuation of its associated pair of devices in a manner determined by the relative degrees of actuation, as respects each other, of the individual devices making up the said associated pair of devices; a plurality of settable means adapted to be set, respectively, by the respective control means; result-producing means associated with the said

settable means, collectively, said settable means, considered collectively, being adapted to control the nature of the action carried out by said result-producing means; means for actuating said result-producing means; and timing means adapted to be actuated when any one of the said plurality of local electrical circuits, which are connected with the said other step switch of said double-step switch means, is closed; a plurality of switches disposed, respectively, in the respective circuits of the said plurality of local electrical circuits, and operatively associated, respectively, with the respective devices of the said second series of devices which is associated with the said one step switch of the said double-step switch means, the switches of said plurality of switches being adapted to be closed, respectively, substantially upon the completion of actuation of their respectively associated devices, said timing means being operative to control the operation of said means for actuating the result-producing means, at the termination of a predetermined time interval.

18. In control apparatus, the combination recited in claim 17, but including, additionally, means for returning the respective operative elements of the apparatus to their original conditions following operation of said result-producing means.

19. In control apparatus, the combination recited in claim 17, wherein the said timing means comprises a pair of substantially similar devices arranged for independent actuation, one of said devices being arranged for actuation when any one of the said plurality of local electrical circuits, which are connected with the said other step switch of said double-step switch means, is closed, and being adapted to cause the operation of said means for actuating the said result-producing means, at the termination of a predetermined time interval, said one device being adapted, further, to cause the actuation of the other of said devices at the termination of a predetermined time interval; and wherein there is, additionally, secondary result-producing means arranged to be controlled in operation by said other device, said other device being adapted to cause actuation of said secondary result-producing means at the termination of a predetermined time interval.

20. In code controlled apparatus provided with code receiving means, means physically responsive to a received code signal; means physically responsive to a thereafter immediately following code space; adjustable regulator means associated with the two said responsive means; and

means for automatically adjusting said regulator means in accordance with the response of the second named physically responsive means.

21. In code controlled apparatus provided with code receiving means, an element movable in response to a received code signal; an element movable in response to a thereafter immediately following code space; movable regulator means; and means for automatically moving said regulator means to positions determined by movements of the second named movable element.

22. In code controlled apparatus provided with code receiving means, the combination of translating means arranged to be actuated, at least in part, by, and for substantially the duration of, the reception of any and every code signal by said code receiving means, and to be actuated, in corresponding part or parts, by any and every code space which immediately follows the said any and every code signal; means for correlating any and every code signal actuation of said translating means which the code space actuation thereof which immediately follows said any and every code signal actuation; and means arranged to be actuated by said correlating means for producing results dependent, in kind, upon the nature of received code signals as compared with the respective immediately following code spaces.

23. In code-controlled apparatus, means for measuring the time length of a received code-signal; means for measuring the time length of a received code-space of the type which occurs between successive code-signals of a group of successive code-signals; and means for comparing the measured code-signal with the measured code-space and for producing a resultant action whose nature depends upon the relative time length of the said measured code-signal.

24. In code-controlled apparatus, means for measuring the respective time lengths of successively received code-signals; means for measuring the time length of each of those received code-spaces which occur first in any group of successively received code-signals; regulator means; means for automatically changing said regulator means to accord with said measured code-spaces; and means for comparing the respective measured code-signals of any group of successively received code-signals with the measured code-space which occurs first in the immediately preceding group and for producing respective resultant actions whose natures depend upon the relative time lengths of the respective measured code-signals.

ARTHUR C. WINTER.
